SIGNALING DEVICE

Mascotte Savage Book, Hermosa Beach, Calif.

Application May 15, 1939, Serial No. 273,648

7 Claims. (Cl. 40—130)

This invention relates to signaling devices.

It is an object of the invention to provide a portable signal which may be used in emergencies by motorists to signal other motorists and pedestrians when it is desired to warn them of danger or indicate the need for help or payment.

A further object of the invention resides in providing a cabinet structure with a two-faced red signal lens in one wall, the top of the cabinet being open and adapted to support a sign and means for supporting a flashlight within the cabinet to illuminate the signal lens and sign at the same time.

Another object of the invention resides in providing a device of the above-mentioned character which is simple and durable in construction, efficient in use, and inexpensive to manufacture.

Other objects and advantages of the invention will be apparent during the course of the following description.

In the accompanying drawings forming a part of this specification and in which like numerals are employed to designate like parts throughout the same,

25 Fig. 1 is an elevation of the signal, viewing the same from the back,

Fig. 2 is a similar view of the front of the signal,

Fig. 3 is a top view of the same,

30 Fig. 4 is a vertical sectional view of the signal,

Fig. 5 is a section taken on line 5—5 of Fig. 4,

Fig. 6 is a detail section taken on line 6—6 of

Fig. 4,

Fig. 7 is a detail section on line 7—7 of Fig. 5,

35 and

Fig. 8 is a view showing various types of sign plates to be used with the signal.

In the drawings, wherein for the purpose of illustration I have shown a preferred embodiment 40 of my invention, the numeral 4 denotes a cabinet or box-like structure having front and back walls 5 and 6, side walls 7, and a weighted bottom 8. The upper portion of the back wall is hingedly connected by hinges 9 to the lower portion so

45 as to permit the upper portion to swing downwardly to form a door 10. The door 10 is held in closed position by a spring catch 11 carried by the door and engages a keeper 12 attached to the side wall of the cabinet. The front wall 5 is provided with an opening 13 covered with wire screening 14 of relatively large mesh. Mounted on the upper part of the screen is a two-faced or

50 double red lens 15, which is illuminated by the flashlight 16 supported within the cabinet. The flashlight is held by a spring clamp 17 having an

arm 18 extending therefrom with a ball 19 at its outer end which is seated in the socket 20 of the bracket 21 attached to the door 10. Thus, it is seen the ball 19 and socket 20 form a swivel joint between the arm 18 and bracket 21 permitting the flashlight to be readily adjusted at any desired angle. The sides of the cabinet at the top and adjacent the back wall are provided with opposed notches 22 which have metal clips 23 disposed therein, and the ends of the clips are 10 fastened to the top edges of the side walls by fasteners 24. The clips 23 are adapted to receive and support sign plates 25 which bridge the top of the cabinet and are illuminated by the flashlight 16. The back of the cabinet has the letters 15 SOS printed thereon for use in the daytime. A series of sign plates 25, each provided with different indicia, as shown in Fig. 8, are provided for use with the signal. The plates not being used are stored within the cabinet, being held against 20 the side wall by a bracket 26.

In use, the portable signal may be used for various purposes, but is of particular use to motorists when traveling on the highways. When a motorist is stalled on the road and in need of 25 help, the signal serves as a convenient means of indicating to other motorists and pedestrians the help desired. It may also be placed in the road or on some part of the vehicle when making repairs on the road to warn other motorists, so as 30 to avoid accidents. The cabinet is placed in an upright position in the desired place, and when the flashlight is turned on it will simultaneously illuminate the red signal lens, at the same time illuminating both sides of the signal plate 35 mounted on top of the cabinet. It will also be observed that by swinging the door of the cabinet down into engagement with the ground, the flashlight will be disposed so that it may be adjusted to direct the light in any desired direction, which 40 will be helpful in illuminating the vehicle while repairing the same at night. In the daytime, the letters SOS on the back wall of the cabinet will serve as a signal.

It is to be understood that the form of my invention herein shown and described is to be taken as a preferred example of the same, and that certain changes in the shape, size, and arrangement of the parts may be made without departing from the spirit of the invention or scope of the subjoined claims.

Having thus described my invention, I claim:

1. A portable signal comprising a cabinet open at the top, a signal lens in the front of said cab-

inet, a sign plate bridging the top of said cabinet, a hinged door at the back of said cabinet adapted to swing downwardly; and illuminating means mounted on said door for lighting said lens and sign plate.

2. A portable signal comprising a cabinet open at the top, a signal lens in the front of said cabinet, a sign plate bridging the top of said cabinet, a flashlight, a spring clamp for supporting said 10 flashlight, a hinged door at the back of said cabinet adapted to swing downwardly; means adjustably connecting said spring clamp to the door of said cabinet, whereby the flashlight may be adjusted to illuminate the signal lens and sign 15 plate.

3. A portable signal comprising a cabinet open at the top, a hinged door at the back of said cabinet, a swivel bracket attached to said door, a spring clamp attached to said bracket, a flashlight supported by said clamp, a signal lens in the front of said cabinet, and sign-holding clips in the upper edges of the side walls of the cabinet.

4. A portable signal comprising a cabinet open 25 at the top and having an opening in the front wall, a screen covering the opening in the front wall, a signal lens mounted on said screen, a sign plate bridging the top of said cabinet, a flashlight, and an adjustable bracket for attaching 30 said flashlight to the back wall, whereby said

flashlight may be positioned to illuminate said signal lens and sign plate.

5. A portable signal comprising a cabinet open at the top and having an opening in the front wall, a screen covering the opening in the front wall, a signal lens mounted on said screen, a sign plate bridging the top of said cabinet, a hinged door in the back of said cabinet mounted to swing downwardly, a swiveled bracket attached to said door, and a flashlight for attaching to said bracket, adapted to illuminate said signal lens and sign plate when said door is open.

6. A portable signal comprising a cabinet open at the top, a signal lens in the front wall of said cabinet, a sign plate bridging the top of said cabinet, the upper portion of the rear wall of said cabinet being hingedly connected to the lower portion to provide a downwardly swinging door, and illuminating means adjustably mounted on the door for simultaneously lighting said lens and sign plate.

7. A portable signal comprising a cabinet, signal means mounted in the front and top of said cabinet, a downwardly swinging door at the rear of said cabinet adapted to swing down into engagement with the supporting surface on which said cabinet is resting, and illuminating means mounted on said door adapted to illuminate said signal means.
